UNITED STATES PATENT OFFICE.

JULES MICHAUD, OF PARIS, FRANCE.

CHROMATIC-PRINTING MACHINE.

SPECIFICATION forming part of Letters Patent No. 449,128, dated March 31, 1891.

Application filed February 10, 1890. Serial No. 339,864. (No model.)

To all whom it may concern.

Be it known that I, JULES MICHAUD, engineer, a citizen of the Republic of France, residing at 96 Rue d'Assas, Paris, have invented 5 a new and useful Chromatic-Printing Machine, of which the following is a specification.

The present invention relates to a printing-machine for producing two or more impressions, either superposed or not, on each side 10 of a sheet of paper during a single passage of the sheet through such machine, the machine being principally intended for producing impressions in two or more colors on each side of the sheet.

15 The machine consists, essentially, of a bed which has a to-and-fro movement imparted thereto either by means of a rack and pinion (as in machines known as "perfecting-machines") or by a crank and connecting-rod, as 20 in most machines for printing on one side only, or in any other suitable manner. On the bed the requisite number of forms are suitably arranged, and above it rotate two cylinders with grippers, one of such cylinders 25 coming in contact with one part or series of "forms" on the bed and serving for the impressions on one side of the sheet to be printed, and the other cylinder coming in contact with the other series of forms and serving for the 30 impressions on the other side of the sheet.

Figure 1 of the accompanying drawings is a vertical section of a machine for producing two impressions on each side of the sheet. Fig. 2 is a side elevation of the arrangement 35 for raising the cylinders 2 and 5, and Figs. 3 and 4 are respectively an end view and side elevation of the arrangement for raising the inking-rollers when they are not required to ink the form passing beneath them.

40 The sheet is fed from table 1 to the grippers of cylinder 2, which carry it forward, so that it comes in contact with form 3 and receives an impression. At the second rotation of the cylinder 2 (the grippers of which have 45 not then released the sheet) such sheet receives a second impression from the form 4 and is then transmitted to the cylinder 5, which by means of its grippers carries same forward and effects the impressions on the 50 opposite side, first by form 6 and then by form 7. The sheet is then seized by the gri-

pers of cylinder 8 and carried forward to the fliers 9, which deliver it to the table 10, in the case where the machine is fitted with a mechanical delivery. The delivery may be 55 effected by a cylinder with grippers or by tapes.

Two ink-ducts are placed one to the right and the other to the left of the impression-cylinders and serve to ink the forms by the 60 intermediary of a series of rollers upon which the distribution is effected until the ink reaches the contact-rollers 11 and 12 on one hand and 13 and 14 on the other hand, which bear directly upon the forms. The rollers 11 65 and 12 serve to ink the forms 4 and 6, and the rollers 13 and 14 serve to ink the forms 3 and 7. It will be understood that I may apply to this machine on one or on both sides either flat or cylindrical ink distribution, as 70 described and shown in the drawings. The contact-roller 11 is raised so as not to ink the part of form 7 which passes under it, and the contact-roller 14 is similarly raised to avoid contact with form 4.

75 Figures 3 and 4 show the arrangement for raising roller 11. At each end of the roller there is a wheel 42. On the bed of the machine and outside the form 4 a lifting-piece 43 is arranged, which acts on the wheel 42 80 and causes the roller to be raised during the whole time that it is over the form 4, which it is not to ink.

I may provide the machine with as many 85 inking apparatus as there are forms—that is to say, as shown in the drawings, a distributing arrangement will supply ink to the contact-rollers 16 and 17 and another to the rollers 18 and 19. In this arrangement the rollers 16 and 17 will ink the form 6, the rollers 90 11 and 12 the form 4, the rollers 13 and 14 the form 7, and the rollers 18 and 19 the form 3. The rollers serving to ink one of the forms will be raised during the passage of the other forms beneath them.

If it is desired to print in one and the same 95 color on each side of the sheet, a single inking apparatus will suffice to ink the forms for printing both sides of the sheet. For this purpose the two rollers 11 and 12 would ink 100 the forms 4 and 6, of which 4 prints on cylinder 2 and 6 on cylinder 5, and the rollers 11

and 12 would therefore suffice to ink the two forms, producing perfecting printing—that is to say, printing on both sides of the sheet. In this case the forms 4 and 6 only would be 5 on the bed, the forms 3 and 7 being removed. The sheet taken by cylinder 2 would first make one rotation with this cylinder without receiving an impression, then a second rotation, during which it would be printed on one 10 side by the form 4. Then being transmitted to cylinder 5, it would first make one rotation, during which it would be printed on the other side of the form 6, and a second rotation without receiving any new impression. Further, 15 the machine may be employed, when desired, in order to produce a single impression only on each side of the sheet, or one of the forms of each set of forms may be replaced by any suitable numbering arrangement.

20 It will be understood that I may apply to this machine either offset-sheets or cleaning-rollers for removing the offset from the second cylinder, as in ordinary perfecting-machines. The table 20 would in the former 25 case serve for feeding the offset-sheets to the cylinder 21, whence cords or tapes would conduct them between the printing-cylinders.

In the case where I employ cleaning-rollers 23 and 24 the latter will remain raised during 30 the passage of the printed sheet and be lowered onto the cylinder 5 when empty.

The machine shown in the drawings will act under conditions analogous to those of an ordinary perfecting-machine. The cylinders 2 and 5 have parts of reduced diameter, so as 35 to avoid battering the forms upon which they are not required to print, or instead of being thus constructed the cylinders may be raised, and they would also have such lifting movement imparted to them so as to hold them away from the bed when moving in a direction opposed to the travel of the latter.

For the purpose of raising the cylinders 2 and 5 they are, as shown in Fig. 2, carried by 45 parts 25 and 26, capable of rising and falling within the frame of the machine. These parts 25 and 26 carry two bearings 27 and 28, the height of which is adjustable by screws. In the bearings 27 and 28 are mounted two pieces 50 29 and 30, which traverse the machine, and themselves receive two arms 31 32. The arms 31 32 at their upper ends abut against fixed points 33 and 34 of the side frame of the machine. Upon a shaft 35, which makes one 55 revolution for each complete travel of the bed of the machine, a cam 36 is fixed and acts upon the cross-piece 37, connected to the pieces 29 and 30. Springs 38 and 39, through the intermediary of the cross-pieces 40 and 41, always 60 tend to raise the parts 25 and 26. The cam 36 causes the pieces 29 and 30 to be alternately inclined and straightened, whereby the rising and falling of the parts 25 and 26 and of the cylinders 2 and 5, which they carry, 65 are effected at the required times.

The movement of opening and closing the grippers is effected under the action of cams mounted upon a movable piece called a "cam-carrier" and operating like the cam-carrier of ordinary perfecting-machines.

The arrangement shown for actuating the ink-distribution apparatus is only shown as a suitable arrangement for such purpose.

The machine shown in the drawings and hereinbefore described is only shown as an 75 example, and it will be understood that I may employ any other suitable arrangements than those described or shown for actuating the bed, and also the cylinders and for either flat or cylindrical inking and for the delivery.

The machine may, when desired, be used as an ordinary perfecting-machine—that is to say, with two forms only, one for printing each side of the sheet, and according to the 85 positions of such forms on the bed they may both be inked by the same contact-rollers or each by different rollers.

The machine may further be employed for printing on one side only of the sheet, either 90 in one or in several colors.

In this invention each of the two impression-cylinders 2 and 5, which are of large diameter, has a portion of its circumference cut away or the radius of one side made shorter 95 than the radius of the opposite side, thus allowing the forms which are not to be printed by each cylinder to pass under it without producing an impression, so that the sheet taken by the grippers of cylinder 2 is printed for 100 the first time by the first form, marked 3 on the drawings, and that while the cylinder continues its movement the second form 7 in its movement comes under the reduced part of cylinder 2, and consequently produces no impression. On the second rotation of cylinder 2 the sheet receives the second impression upon the third form, marked 4 on the drawings, and while the cylinder continues its movement the fourth form 6 comes under the 105 reduced part of cylinder 2, and consequently produces no impression. The sheet, having thus received two impressions on the same side, passes to and is reversed upon cylinder 5 and receives two impressions on the second 110 side when it passes over forms 6 and 7, the forms 4 and 3, which both come under the reduced part of cylinder 5, producing no impression thereon. As in all perfecting-machines, when the cylinder 2 carries the sheet 115 the cylinder 5 is raised by any suitable means so as not to touch the forms, while, on the contrary, when the cylinder 5 carries the sheet the cylinder 2 is raised so as not to touch the forms. The two impressions on the same 120 side are produced by alternate forms—that is to say, by the first and third forms—which enables the machine to be made with a shorter travel.

In this machine only two ink-duets and two 125

ink-distributing systems are requisite to obtain two colors—say red and blue—on each side of the sheet.

What I claim as my invention, and desire 5 to secure by Letters Patent, is—

The combination of two impression-cylinders provided with grippers, a bed carrying two series of forms, the forms of each series alternating with those of the other series, 10 those of one set serving to produce impressions on one side of a sheet of paper while such sheet is on one cylinder, while the forms

of the other set produce the impressions on the opposite side of the sheet when same has been transferred to the other cylinder, the alternate forms being caused to pass under the cylinder with which they are not required to act without coming in contact therewith, all substantially as set forth.

JULES MICHAUD.
